UNITED STATES PATENT OFFICE.

LAWRENCE CONNELL, JR., OF PORTLAND, OREGON.

TELEGRAPHY.

Application filed December 2, 1921. Serial No. 519,433.

To all whom it may concern:

Be it known that I, LAWRENCE CONNELL, Jr., a citizen of the United States, and a resident of the city of Portland, county of 5 Multnomah, and State of Oregon, have invented a certain new and useful Improvement in Telegraphy, of which the following is a specification.

The object of my invention is to provide a 10 method and means which will facilitate the sending of messages by telegraphy.

I attain this end through providing a system of signals each composed of two or more elements, preferably using the 15 smaller number, in which each element occurs but once in a signal. Each element in a signal is composed of one or more units of predetermined length and each signal is formed and determined by the relative 20 lengths, or by the relative lengths and sequence, of the elements composing the signal. I also provide means whereby the transmission of my signals can be expedited.

As is understood by all those versed in 25 the art, telegraphy has been hampered by such factors as retardation, inertia of the repeating and receiving apparatus and other physical properties, which slow up the transmission.

Some of the benefits of my invention are: 30 First, it provides codes of shorter average signal lengths.

Second, it reduces the losses from channel retardation.

Third, it reduces the losses from inertia 35 of main line apparatus.

Fourth, it provides a system especially 40 adapted to the use of all-electrical apparatus for the attainment of maximum speed in the selection and recording of printed characters.

Fifth, it provides a system adapted to 45 greater range of circuit variation, and to new classes of operation as well as to the present classes, both manual and automatic.

To explain more fully, under the above 50 headings:

First. In comparing the average signals 55 of my codes with those of the commonly used codes, Morse, Continental and Baudot, it is necessary to consider the average signal used in the transmission of a comparatively large number of characters, as in my codes together with Morse and Continental, advantage can be taken of character frequency by assigning the shorter signals to the more

frequently used characters, while in Baudot the signals are all of five units length. For instance, while the average signal of the thirty-six signals making up the Morse alphabet is approximately 10.86 units in length and the average signal of the thirty-six signals of the Continental alphabet is approximately 12.47 units in length, it has been found from studies which have been 60 made that the average Morse combination used in the actual transmission of commercial telegrams is approximately 8 units, and that in Continental 9 units; in other words, character frequency reduces the average signal of the Morse alphabet approximately 26.34 per cent and that of the Continental alphabet approximately 27.84 per cent. 65

The length of the average signal of the 70 thirty six shortest signals of my two element alphabet, when the alphabet is extended to forty nine characters by utilizing elements up to seven units in length, is 6.722 units. Reducing this figure by the percentage used in the Morse reduction gives approximately 4.95 units, while reducing it by the percentage used in the Continental reduction gives approximately 4.85 units for the average signal combination of my two 75 element code under working conditions. Likewise, the average signal of the thirty six characters shown in my three element code is 4.166 units in length and reducing this gives 3.06 units and 3.01 units, respectively, as the average signal combination according to the Morse and Continental reductions. 80

In comparing with Baudot, it must be 85 taken into consideration that the use of Baudot in this country is practically confined to printer operation and that its alphabet is not complete, there being only thirty two available signals. Except in multiplex operation it has been found necessary to use additional units in the transmission of each signal to care for apparatus functions, etc., and in any printer operation the incompleteness of the alphabet necessitates the use of upper and lower case 90 characters, making it necessary to transmit three signals for each upper case character that occurs between two lower case characters. 100

It is obvious that no comparison of these 110 codes could be absolutely exact and that the recognized average signal lengths of the

commonly used codes are only approximate. Considering these points, a very generous comparison in favor of the commonly used codes would be: Continental 9 units, Morse 8 units, Baudot, except in multiplex operation, 8 units, Baudot, in multiplex operation, 5 units plus, my two element code 5 units minus, my three element code 3 units plus.

Second. The majority of circuits, as at present operated, are retarded by the inductance and electrostatic capacity of the main circuits and included apparatus to a degree that keeps the speed of signalling considerably below the capacity of the operators when manual operation is employed; and printer operation is practicable over only comparatively non-retarded circuits. The manifestation of these retarding factors is to prolong the time during which it is necessary to apply an electrical change at the home end of a circuit to induce the required resultant electrical change at its distant end, and to cause the delayed appearance of current at the distant end to occur as a gradual rise or fall as compared with the abrupt application at the home end. In other words, retardation prolongs the time necessary to complete an electrical change in a circuit; and it is principally the effects of retardation upon the code and system used that limits the practical length of circuits.

The commonly used systems suffer excessively from retardation because their signals cause a maximum of electrical changes in the channels. Some of their signals cause actual changes at the rate of one for each unit of which the signal is composed, and the others that do not cause the actual number of changes corresponding to the number of units in the signal, do cause changes at the same rate of speed as the length of the basic units of the signals is the same in all the signals of an alphabet under a given rate of operation. Therefore, from the standpoint of retardation and average signal length, the average signal of Morse, Continental and Baudot (except in multiplex operation) may be considered as of approximately 8 units length and as causing electrical changes in the channel at the rate of 8 per signal. The loss from retardation is consequently approximately eight times the loss incident to one electrical change in the channel.

My system reduces the retardation loss to a minimum by causing only one electrical change for each element of which a signal is composed. Thus, my two element code causes only two electrical changes per signal, and the loss per signal is only two times the loss to one electrical change in the channel, instead of eight times as in the commonly used codes. My sending apparatus automatically lengthens each element the de-

sired degree to compensate for retardation and the receiving apparatus discards the additions from the signals. It is obvious that the signals of my codes which are made up of elements each composed of several units could be transmitted over circuits of moderate retardation without any lengthening of the elements; but the signals which have elements of only one or two units must be lengthened for transmission over such circuits, which necessitates the lengthening of all the signals in the alphabet a corresponding degree.

To explain more fully the comparative effects of retardation I will assume the transmission of the average signal of the commonly used codes and the average signal of my two element code over three classes of circuits, the first being a circuit of no appreciable retardation over which an electrical change can be accomplished in one unit of time, the second a circuit of moderate retardation over which the electrical change consumes two units of time and the third a circuit of greater retardation over which the electrical change consumes three units of time. The transmission of the average signal of the commonly used codes would consume approximately eight units of time over the first circuit, approximately sixteen units of time over the second circuit and approximately twenty four units of time over the third circuit, as each unit of the signal can be transmitted no faster than the time required to complete one electrical change in these respective circuits. The transmission of the average signal of my two element code would be accomplished over the first circuit in approximately five units of time, over the second circuit in approximately seven units of time and over the third circuit in approximately nine units of time, each element being lengthened one unit for transmission over the second circuit and two units for transmission over the third circuit.

Third. The current strength available in main circuits is very limited, which causes a loss from inertia due to moving the armatures of the receiving and repeating relays that are energized by the main circuits from positions of rest by a feeble force. In the commonly used systems these main line instruments are either required to cooperate directly with the units of the signals, or else to operate at the same rate of speed and the length of each unit of the signal must accordingly be increased to overcome this loss the same as for channel retardation. In my system the unit operation is accomplished in the local circuits of the receiving apparatus, where comparatively unlimited current strength is available to force the movement of armatures and where the apparatus can be better designed

for speed at the expense of wasted current strength. I overcome this inertia loss by the same means that I use to overcome retardation, that is, each element of my signals may be lengthened, thereby allowing the line instruments to operate at lower speed, while the local instruments of the receiving apparatus may continue to operate at maximum speed, merely discarding the additions from the signals.

Fourth. It is well known that the selection and recording of signals in the present automatic printer systems is limited in speed considerably below the speed at which the signals can be transmitted. The fault lies in the construction of the codes employed which necessitate, in addition to a primary reception of the signals by fast line controlled relays or similar apparatus, a secondary mechanical selection of the characters represented that is comparatively slow and lags behind the primary selection. The construction of my codes make them especially adapted to the attainment of high speed in selecting and recording, principally due to the fact that the units of each element follow each other consecutively and are of the same length, thereby permitting the selection to be made entirely by primary and positive actions in which all the movements are similar and of minimum distance of travel. For instance, the selection of type-writer units in my two element printer system is effected by disintegrating the continuous pulse that represents an element of a signal into as many pulses of local current as there are units in the element; and by requiring each of these resultant pulses merely to move the armature of a relay from one of its stops to the other to accomplish the selection. No secondary mechanical selection is necessary. It is evident that such primary and positive movements, forced by ample local energy, can be accomplished at greater speed than that at which the units of a signal can be transmitted over a main channel. I have designed my apparatus to be practically all-electrical and have reduced mechanical movements to a minimum. This feature of my invention will be apparent from the description of the apparatus.

Fifth. The present systems are limited in respect to the classes of operation to which they are applicable and the range of circuit variation over which they are efficient. The use of Baudot is confined to automatic reception over circuits of comparatively little retardation, while Morse and Continental are poorly adapted to printer operation, or to the attainment of speed over fast circuits on account of the length of their signals. My system is applicable to all the present classes of operation, both manual and automatic, as the descriptions of apparatus will indicate. By reason of the

shortness of its signals it is adapted to fast transmission over good circuits; and by reason of its comparative immunity from the effects of retardation it is not only adapted to faster and more efficient work on the more heavily retarded circuits now in use, but also on circuits of greater length than can be efficiently operated by the present systems. My three element system (which utilizes a combination of elements that has always existed in polar duplex operation but which the present systems have been unable to make use of on account of the mixed order of occurrence of the elements composing their signals) is an example of the adaptability of my invention to new methods of operation. The extreme shortness of the average signal of this code adapts it to the attainment of much greater speed than any of the systems now in use, particularly over first class circuits.

The application of my invention to the common forms of telegraphy, printer, multiplex and manual and to a new three element system, is shown in the accompanying diagrammatic drawings, of which:—

Fig. 1 shows thirty six signals of a two element code, in unit of length form;

Fig. 2 shows the same code and signals in unit of dot form;

Fig. 3 shows a section of tape with the same signals perforated therein, to be used in connection with my two element transmitter;

Fig. 4 shows a three element code; 100

Fig. 5 shows a section of tape to be used in connection with my two element transmitter;

Figs. 6 and 6^a show a keyboard operated perforator for preparing the tape shown in Fig. 3; 105

Fig. 7 shows a transmitting apparatus for a two element printer system.

Fig. 8 shows a receiving apparatus for a two element printer system; 110

Fig. 9 shows modified apparatus adapted for using my two element system adapted to multiplex operation;

Fig. 10 shows a modified transmitting apparatus especially adapted to use my three element system; 115

Figs. 11 and 11^a show a modified receiving apparatus especially adapted to use my three element system; and

Fig. 12 shows a two element system for manual operation.

Describing first the code shown in Fig. 1:—

The heavy horizontal lines, as *a*, designate continuous pulses of mark current and the lighter horizontal lines, as *b*, designate continuous pulses of space current. The spaces between the vertical lines represent units of length. Thus, the first signal at the top, *c*, is made up of a mark pulse 120

one unit in length, followed by a space pulse one unit in length; and the bottom signal, *d*, is composed of a mark pulse six units in length, followed by a space pulse six units in length.

Describing next the code shown in Fig. 2:

In this code the continuous pulses shown in Fig. 1 are merely broken up into the 10 number of dots that could be made at a predetermined rate of speed during the duration of the continuous pulses. The signals are arranged in the same order as those in Fig. 1, the vertical line *a* dividing 15 the mark dots from the space dots. Thus, the first signal *b* represents one mark dot, followed by one space dot, and the last signal *c* represents six mark dots, followed by six space dots.

20 Describing next the tape shown in Fig. 3:

The vertical row of holes *a*, extending up the center of the tape, designates feed holes, to be engaged by the teeth of a sprocket wheel for the purpose of feeding the tape 25 through the transmitter. The perforations to the left of the row of feed holes, as *b*, designate mark perforations and those to the right, as *c*, designate space perforations. The number of dots, or units, 30 in the mark pulse of each signal is read by its distance to the left of the row of feed holes, and the number in the space pulse is read by its distance to the right of the feed holes, the unit of measurement 35 being the space between the vertical lines. Thus, the first signal at the top is shown to consist of one mark dot, by perforation *b*, and one space dot, by perforation *c*; these perforations being one unit distant to the left and right, respectively, of feed hole *d*. The last signal designates six 40 mark dots by perforation *e* being positioned six units to the left of feed hole *f*, and six space dots by perforation *g* being positioned six units to the right of the same 45 feed hole.

Describing next the code shown in Fig. 4;

The heavy horizontal lines, as *a*, designate the first element, such as positive; 50 the lighter horizontal lines, as *b*, designate the second element, such as negative, and the crossed horizontal lines, as *c*, designate the third element, such as zero. The spaces between the vertical lines designate units 55 of time. Thus, the first signal at the top consists of one unit of the first element, followed by one unit of the third element, and the last signal consists of one unit of the second element, followed by three units 60 of the first element, followed by one unit of the third element. All the signals end with one or more units of the third element.

Describing next the perforated tape shown in Fig. 5:

65 The perforations in the vertical row *a*

designate feed holes; those in the vertical row *b* represent the first element perforations; those in the vertical row *c* represent the second element perforations, and those in the vertical row *d* represent the third 70 element perforations. The number of units of each element in the signals are read by the number of horizontal lines, representing units of time, between the perforation indicating one of the elements and the next 75 perforation below, representing another element. Thus, the first signal at the top, represents one unit of the first element, followed by one unit of the third element. The second signal commences with the perforation *e* and represents one unit of the first element, followed by two units of the third element; there being two horizontal lines between the perforation *f* which represents 80 the commencement of the third element, and the perforation *g* which represents the end of the third element and the commencement 85 of the next signal. The third signal, which starts with the perforation *g*, represents one unit of the first element, followed by one unit of the second element, followed by one unit of the third element.

Describing next the apparatus shown in Figs. 6 and 6^a:

Fig. 6 designates a key board and key levers as of an ordinary typewriter, looking at it from above, of which *b*² and *c*² are two complete key levers, pivoted at *d*² and *e*² respectively. The other key levers are shown broken off near the letter caps, as indicated at *f*², but are assumed to be arranged similarly to levers *b*² and *c*². *g*², *h*², *i*², *j*², *k*², *l*², *m*², *n*², *o*², *p*², *q*² and *r*² designate 100 twelve contact levers, pivoted at *s*², *t*², *u*², *v*², *w*², *x*², *y*², *z*², 105 22, 23, 24 and 25, respectively, extending beneath the key levers at right angles thereto and each adapted to make an electrical contact at its free end when forced downward by one of the key levers. 26 designates a stop against which the contact levers normally bear upward 110 under the force of springs (not shown), the upper surface of the contact levers being thus normally held a short distance below the bottom of the key levers.

Referring to Fig. 6^a:

27 designates an edge view of the apparatus shown in Fig. 6, of which 28 is a key lever pivoted at 29, normally held against stop 210 by spring 211 and carrying 115 projecting knobs 212 and 213 on its lower edge. 214, 215, 216, 217, 218, 219, 220, 221, 222, 223, 224 and 225 are the free ends of the twelve contact levers shown in *a*², electrically connected; and 226, 227, 228, 229, 230, 231, 232, 233, 234, 235, 236 and 237 are 120 their associated contact points, respectively.

280 designates a tape perforator comprising mark perforating needles 238, 239, 240, 241, 242 and 243 and space perforating 125 130

- needles 244, 245, 246, 247, 248 and 249, all held in the slotted form 250 and each having a spring, as 251 of mark needle 243, which normally hold the needles away from the tape; feed hole perforating needle 252 and die 253. The tape, a section of which is shown at 254, is fed forward between the die and the perforating needles by mechanism not shown.
- 10 Each perforating needle is operated by an individual electromagnetic hammer device, all of which are similar and may be described by referring to device 255 which controls mark needle 238. It comprises electromagnet 256, armature 257, spring 258 and back stop 259. When magnet 256 is energized armature 257 is drawn toward it and strikes against needle 238, forcing the latter through the tape. When magnet 256 is deenergized armature 257 is pulled back against stop 259 by spring 258, which allows perforating needle 238 to disengage the tape and resume its normal position as shown in the drawing.
- 25 The operation is as follows: When key lever 28 of keyboard 27 is depressed knobs 212 and 213 engage contact levers 219 and 221 and force the latter down against contacts 231 and 233, respectively. This energizes hammer device 255 through the local circuit comprising battery 260, conductor 261, contact lever 219, contact 231, conductor 262, the coil of magnet 256, conductors 263 and 264, the coil of magnet 265 and conductor 266, and simultaneously energizes hammer device 267 through the same local circuit and also hammer device 268 through the local circuit comprising battery 260, conductor 261, contact lever 221, contact 233, conductor 269, the coil of magnet 270, conductors 271 and 272, resistance 273 and conductor 266. Mark needle 238, space needle 245 and feed hole needle 252 are accordingly driven through the tape, simultaneously. The signal punched represents one mark and two space units. When key lever 28 is released the hammer devices are deenergized and allow the perforating needles to disengage the tape as explained, and the tape is then moved forward a predetermined distance for the next signal by mechanism (not shown) such as is used to feed the ribbon of a typewriter.
- 55 The remaining key levers select the desired mark and space perforating needles in the same manner, each key lever having two knobs on its lower edge positioned to engage the particular contact levers that control the hammer device associated with the particular mark and space needles that the key lever is designed to select.
- 60 Thus, the key lever representing the signal composed of six mark units and one space unit would have a knob directly above the contact lever 214, instead of in the position of knob 212 in the drawing, and a knob above contact lever 220 instead of in the position of knob 213 in the drawing; and when depressed, such a key lever would select hammer devices 274, 275 and 267, thereby operating mark needle 243 representing six mark units, space needle 244 representing one space unit, and feed hole needle 252. The hammer device 267, which operates the feed hole needle 252, is energized each time a signal selection is made, its coil being included in the local circuit of each mark needle hammer device.
- 75 To punch feed holes only, a key is provided having only one projecting knob on its lower edge, positioned to engage a thirteenth contact lever, as 276 of keyboard 27. When this key is depressed, the local circuit comprising battery 260, conductor 261, contact lever 276, contact 277, conductor 278, resistance 279, conductor 264, the coil of magnet 265 and conductor 266 is closed and hammer device 267 alone is energized and operates feed hole perforating needle 252. The mechanism for moving the tape forward operates when feed holes are being punched, the same as when signals are punched.
- 80 Describing next the apparatus shown in Fig. 7:
- 85 a^3 designates a vibrator comprising stationary support b^3 , in which vibrating spring c^3 is rigidly held; vibrating rod d^3 attached to the free end of spring c^3 and carrying spring contact e^3 and slidable weight f^3 ; and contact g^3 , with which spring e^3 makes contact once every cycle of vibration and thereby energizes vibrator magnet h^3 through the local circuit comprising battery i^3 , conductor j^3 , vibrator a^3 , contact g^3 , conductors k^3 and l^3 , the coil of magnet m^3 , conductors n^3 and o^3 , resistance p^3 and conductors q^3 and r^3 . The ohmic resistance of the resistance 3^p and the coils of the magnets 3^h and 3^m and the conductor 3^r is of such value that the current divides and some flows thru the circuit previously mentioned and the remainder passes from the conductor 3^k thru the conductor 3^z , armature 3^t , conductor 3^y and resistance 3^p . The pull of this magnet on vibrator rod d^3 at the proper point in its swing imparts the necessary additional energy to the vibrator to maintain its vibrations in the well understood manner.
- 90 s^3 designates a pulse regulating relay, the coil of whose magnet m^3 is included in the above described circuit of the coil of vibrator magnet h^3 . When the circuit is energized, armature t^3 engages front contact u^3 , thereby closing the shunt circuit comprising conductor x^3 , contact u^3 , armature t^3 and conductor y^3 across the battery leads h^3 and r^3 , which supply the vibrator battery current to the apparatus yet to be described.
- 95
- 100
- 105
- 110
- 115
- 120
- 125
- 130

When magnet m^3 is deenergized, armature t^3 engages back contact v^3 , under the pull of spring w^3 , and a similar shunt circuit is closed, conductor z^3 and contact v^3 merely being substituted for conductor x^3 and contact u^3 . This relay allows the vibrator battery current to flow to the apparatus yet to be described only when its armature t^3 is between stops and is moving from back contact v^3 to front contact u^3 . No current flows when this armature moves back to contact v^3 because this movement occurs while the circuit is open at contact g^3 , of vibrator a^3 .

15 32 designates a group of differentially wound polarized relays, connected in multiple across the vibrator battery leads k^3 and r^3 , as follows: relay 33 through conductor 312, coil 311 and conductor 310; relay 34 through conductor 313, coil 314, conductor 315, contact 316 and armature 317 of relay 33 and conductor 318; relay 35 through conductor 319, coil 320, conductor 321, contact 322, armature 323 and conductor 324; relay 36 through conductor 325, coil 326, conductor 327, contact 328, armature 329 and conductor 330; relay 37 through conductor 331, coil 332, conductor 333, contact 334, armature 335 and conductor 336; relay 38 through conductor 337, coil 338, conductor 339, contact 340, armature 341 and conductor 342, and relay 39 through conductor 343, coil 344, conductor 345, contact 346, armature 347 and conductor 348. The circuits that connect the above mentioned coils of relays 34, 35, 36, 37, 38 and 39 with vibrator battery leads k^3 and r^3 are thus normally open until the armature of the next relay to the left engages its right hand contact, while the coil 311 of relay 33 is always on a closed circuit across these leads. The effect of these coils, when energized, is to move their respective armatures to the right. The relays are arranged, so that their armatures will remain against either stop when the relays are not energized, and the distance of armature travel between front and back stops is regulated so that any one pulse transmitted by vibrator a^3 and shortened by pulse regulator s^3 will be sufficient only to move the armature of any one of these relays from its back contact to its front contact, and not leave any lapover of current to effect the next relay to the right through the circuit closed by such a movement of one of these armatures. Hence, relay 33 will set, or move its armature to the right, on the first pulse of current transmitted by vibrator a^3 and relay 34 will act likewise on the second pulse, relay 35 on the third pulse, relay 36 on the fourth pulse, relay 37 on the fifth pulse, relays 38 on the sixth pulse and relay 39 on the seventh pulse.

65 349 designates a signal selecting apparatus,

which automatically handles the perforated tape shown in Fig. 3, and selects the signals by the perforations therein. 350 represents a cross section of tape cut across the perforations comprising one signal. The tape is shown as travelling upward through the plane of the drawing, and perpendicular thereto. 351 represents the mark perforation, 352 the feed hole perforation and 353 the space perforation. 354, 355, 356, 357, 358 and 359 and the sixth, fifth, fourth, third, second and first mark selecting needles, respectively, held in a slotted form (not shown) beneath the tape, so that their upper tips are directly beneath the points in the tape where the perforations should occur that represent the sixth, fifth, fourth, third, second and first mark units, respectively, when the tape is in position to register a signal. 365, 366, 367, 368, 369 and 370 represent the first, second, third, fourth, fifth and sixth space selecting needles, respectively, which are likewise positioned beneath the tape where the first, second, third, fourth, fifth and sixth space perforations, respectively, should occur. The six mark needles are electrically connected with each other, as indicated at 360, and the six space needles are likewise connected. The needles are otherwise similar, each having a projecting knob, as 361 of needle 354; a contact making extension at its lower end, as 362 of the same needle; a contact point associated therewith, as 363 of the same needle, and a compression spring underneath its lower end to force the needle upward into engagement with its associated contact point, when the needle is otherwise free to rise, as 364 of the same needle. 371 and 372 are two needle controlling levers, operable between stops 373 and 374, and 375 and 376, respectively, by the pull of magnet 377 against spring 378 and the pull of magnet 379 against spring 380, respectively. Magnet 377 is energized and holds lever 371 down during the time magnet 379 is deenergized and lever 372 accordingly pulled up against its upper stop 375 by spring 380, and vice versa, through the two local circuits, the first comprising battery 381, armature 382, contact 383, conductor 384, the coil of magnet 377 and conductors 385 and 386 and the second comprising battery 381, armature 382, contact 387, conductor 388, the coil of magnet 379 and conductors 389 and 390; these respective circuits being active and inactive accordingly as armature 382 engages one or the other of its contacts 383 and 387. When either lever is down, the needles controlled by it are prevented from rising by the knobs, as 361 of needle 354, engaging the bottom of the lever. When either lever is up the needles controlled by it are free to rise if a perforation occurs above them, as indicated by space needle 370 which is shown projecting

through space perforation 353 in the tape; and the needles that are positioned below the unperforated portion of the tape are held down by the tape itself. The contact points 5 associated with each mark needle is electrically connected with the contact associated with the corresponding space needle, as indicated by conductor 390 joining the contact points associated with the first mark and first space needles, conductor 391 joining the contact points associated with the second mark and space needles, conductor 392 joining the contact points associated with the third mark and space needles, conductor 393 10 joining the contact points associated with the fourth mark and space needles, conductor 394 joining the contact points associated with the fifth mark and space needles and conductor 395 joining the contact points 15 associated with the sixth mark and space needles. Each pair of contacts thus joined is connected with one of the timing relays, as indicated by the extension of conductor 390 to contact 322 of timing relay 34; conductor 391 to contact 328 of relay 35; conductor 392 to contact 334 of relay 36; conductor 393 to contact 340 of relay 37; conductor 394 to contact 346 of relay 38, and conductor 395 to contact 396 of relay 39. 20 This connects any needle that engages its associated contact point with the vibrator battery lead r^3 , through the armature and right hand contact point of the timing relay with which it is connected, when the armature of that particular relay engages its right hand contact. 397 is an end view of the sprocket wheel, the teeth of which engage the feed holes in the tape and move the tape forward the distance of one feed hole 25 at a time, in the well understood manner.

398 and 399 are differentially wound polarized relays, one coil of each being connected with the mark needles through conductor 3100, coil 3101 of relay 399, conductor 3102 and coil 3103 of relay 398. The other coil of each relay is connected with the space needles through conductor 3104, coil 3105 of relay 399, conductor 3106 and coil 3107 of relay 398. The windings are 30 disposed to move the armatures of these relays in the direction indicated by the arrows on the coils. Relay 399 is the line transmitter proper, by means of which the signals are applied to the line; and relay 398 controls the needle controlling levers through the local circuits already described.

3111 designates a reset relay, comprising armature 3112, having spring contact 3113 at its upper end; spring 3114; front and back stops 3115 and 3116, respectively; contact point 3117 and magnet 3118. The coil of the latter is included in the circuit connecting relay 398 with battery lead k^3 , comprising conductor 3119 which connects 35 with both coils of relay 398 at the point 3120, the winding of magnet 3118; and conductor 3121. The contact 3117 and spring contact 3113 of relay 3111 control the reset coils of the timing relays 32 through the local circuit comprising battery 3122, conductor 3123, coil 3124 of relay 39, conductor 3125, coil 3126 of relay 38, conductor 3127, coil 3128 of relay 37, conductor 3129, coil 3130 of relay 36, conductor 3131, coil 3132 of relay 35, conductor 3133, coil 3134 of relay 34, conductor 3135, coil 3136 of relay 33, conductor 3137, armature 3112 of reset relay 3111, spring contact 3113, contact point 3117 and conductor 3138. 40 The operation of the apparatus constructed and arranged as described is as follows:

The various parts are shown in the drawing as they should be at the commencement of the transmission of the space pulse of a signal. The transmission of the mark pulse 45 has just been completed. Space needle 370 is in contact with its associated contact point, its upper end projecting through space perforation 353 which designates six units as the length of the space pulse to be 50 transmitted. The other space needles are held down by the unperforated portion of the tape and the mark needles are held down by needle controlling lever 371.

The first pulse of current transmitted by 55 vibrator a^3 and shortened by pulse regulating relay s^3 will pass through the coil 311 of timing relay 33 and cause that relay to move its armature 317 to the right and engage contact 316, which closes the circuit 60 connecting the coil 314 of relay 34 across the battery leads r^3 and k^3 , but just too late to be energized by the pulse that moves the armature of relay 33. Relay 34 will then 65 set on the second pulse, relay 35 on the third pulse, relay 36 on the fourth pulse, relay 37 on the fifth pulse and relay 38 on the sixth pulse. The seventh pulse will likewise set the armature of relay 39 into contact with point 396, which will close across the leads k^3 and r^3 , the circuit comprising 70 the armature of relay 39, contact 396, conductor 395, the contact point associated with space needle 370, space needle 370, conductor 3104, coil 3105 of relay 399, conductor 3106, coil 3107 of relay 398, conductor 3119, the coil of magnet 3118 of reset relay 3111 and conductor 3121; but no current will flow through this circuit on the seventh pulse 75 for the same reasons that govern the setting of the timing relays.

The eighth pulse will energize this circuit and cause the line transmitter 399 to move its armature to contact 3109, needle regulating relay 398 to move its armature to contact 387 and reset relay 3111 to close momentarily against contact 3117 and then resume its open position. The results of these actions will be as follows: Line transmitter relay 399 will terminate the applica- 80

tion of the space electrical element to the line and will apply the mark electrical element in its stead; reset relay 3111 will put a momentary pulse of current from the 5 reset battery 3122 through the reset coils of all the timing relays and cause them to move their armatures into the reset positions, against their left hand stops; needle controlling relay 398 will open the 10 local circuit of magnet 377, thereby causing needle controlling lever 371 to move up against stop 373 and liberate the mark needles to rise and engage the tape, and will close the local circuit of magnet 379 15 thereby causing the needle controlling lever 372 to be drawn down against stop 376, which will force the space needles downward out of engagement with the tape and move the tape forward to the next signal 20 by turning the sprocket wheel 397 forward one tooth's distance, as explained.

It is evident that two extra units were added to the space pulse of the signal that was transmitted as described, as the tape indicates a six unit pulse, while eight pulses of the vibrator current were consumed in registering it. These two added units represent the lengthening of the pulse sent through the channel of communication to 30 compensate for the retardation losses therein. If such lengthening of signals is not desired, the timing relays 33 and 34 can be made inoperative by screwing the contact points against their armatures so that 35 these armatures are held firmly against their right hand contacts. The first pulse of the vibrator current will then operate relay 35 and, if the signal being registered is a one unit signal, the first pulse will flow 40 through conductor 390 and register the signal. If one added unit is desired, relay 33 can be made inoperative, and relay 34 left operative as shown.

Assuming that the operation already described was done in registering the space pulse of the preceding signal on the tape, and that the tape as shown in the drawing has just been moved forward as described, the transmission of the signal indicated on 45 the tape will be as follows: Mark needle 357 will rise through mark perforation 351 and engage its associated contact. The armatures of the timing relays are already reset and resting against their left hand stops. 50 The first pulse of vibrator current will set timing relay 33; timing relays 34, 35, 36 following on the second, third and fourth pulses, respectively. The fifth pulse will flow through conductor 392 to the contact 55 point associated with mark needle 357, thence to conductor 3100 through needle 357, conductor 360 and needle 354, thence through coil 3101 of relay 399, coil 3103 of relay 398 and, from the point 3120, through the same 60 path to battery lead k^3 as described for the 65

space pulse action. The armatures of relays 399 and 398 will move in the direction shown by the arrows on the coils that are thus energized, and will consequently resume the positions shown in the drawing. 70 Reset relay 3111 will act again in the same manner as before, thereby resetting the timing relay armatures, and the apparatus will commence to register the space pulse of the signal—for which the operation has been described. 75

Describing next the apparatus shown in Fig. 8:

a^4, b^4, c^4, d^4, e^4 and f^4 designate a group of six differentially wound polarized relays, serving as mark selecting relays. a^4 is an extra dot, or signal lengthening relay, which serves the same purpose as timing relays 33 and 34 of the transmitting apparatus shown in Fig. 7 and b^4, c^4, d^4, e^4 and f^4 operate to select one of six circuits through the typewriter units. This group of relays set, one after the other, on a series of current pulses, the same as do the timing relays of the transmitter, the contact points that close the setting circuits for the next succeeding relays in the described order being g^4 of relay a^4 , h^4 of relay b^4 , i^4 of relay c^4 , j^4 of relay d^4 and k^4 of relay e^4 . The armatures of relays b^4, c^4, d^4 and e^4 have insulated contact tips, as indicated at insulation l^4 of the armature of relay b^4 . This group controls the selection of paths through the typewriter magnet units, as follows: Battery lead m^4 is applied to conductor n^4 when the armature of relay b^4 engages contact o^4 ; it is applied to conductor p^4 when relay b^4 has set, or moved its armature into engagement with contact q^4 and before relay c^4 has set; and in the same manner the conductores r^4, s^4, t^4 and u^4 are selected and connected with battery lead m^4 according to the number of relays set. 100

$v^4, w^4, x^4, y^4, z^4, 42$ and 43 designate a similar group of seven space selecting relays, for selecting one of the six typewriter circuits 44, 45, 46, 47, 48 and 49 and connecting it with battery lead 410, accordingly as relays $v^4, w^4, x^4, y^4, z^4, 42$ and 43 set on the first, second, third, fourth, fifth and sixth pulses, respectively; relay v^4 being an extra dot, or signal lengthening relay. 110

411 designates a vibrator controlling the setting of the space selecting relays through the battery 412, conductor 413, contact 414, resistance 415, and the leads 416 and 417 across which the space selecting relays are connected in multiple in the manner described for the timing relays of the transmitter, and across which pulse regulating relay 418 is also connected through the circuit comprising resistance 419, conductor 420, the coil of magnet 421 and conductor 422 for applying the shunts comprising conductor 423, armature 424 and contact 425, and conductor 423, armature 424, contact 426 and con- 115 120 125 130 135 140 145 150 155 160 165 170 175 180

ductor 427 around the space selecting relays in the manner described for the same class relay of the transmitting apparatus.

428 designates a vibrator, controlling the setting of the mark group of selecting relays through the battery 412, conductors 413 and 429, contact 430, conductor 431, contact 432, contact strip 433, conductor 434, resistance 435 and the leads 436 and 417 across which the mark selecting relays and the pulse regulating relay 437 are connected in the same manner as the similar space apparatus is connected across the space leads 416 and 417.

15 438 designates a polarized relay whose purpose is to eliminate the first pulse of current to the mark selecting relays each time mark vibrator 428 is released to vibrate, which is accomplished by the opening of the circuit of the lead 436 at the contacts 432 and 433; and to open the typewriter battery circuit after the first contact has been made by mark vibrator 428, which is accomplished in connection with other apparatus by the disengaging of its armature 439 from contact 440. The armature 439 is insulated at 441 to separate the two mentioned circuits.

30 442 designates a relay controlling the typewriter battery 443, through its armature 444 and front contact 445.

446 designates the armature of the receiving relay of the set, which is assumed to be controlled by a transmitting apparatus at a distant station, through a channel 4446^a and a relay 4446^b which is returned by a spring 4446^c. It controls, through battery 447, two local circuits, the first comprising back contact 448 of the receiving relay, conductor 449, the coil of magnet 450 of mark vibrator 428, conductor 451, the coil of magnet 452 of polarized relay 438 and conductors 453 and 454, and the second comprising front contact 455 of the receiving relay, conductor 456, the coil of magnet 457 of space vibrator 411, conductor 458, the coil of magnet 459 of relay 442 and conductors 460 and 454; one of these circuits being active and the other open accordingly as this armature 50 engages one or the other of its contacts under the control of the mark and space pulses of current coming over the channel from the sending station. When the former circuit is closed, the armature of relay 438 is moved against contact 440; and magnet 450 of mark vibrator 428 draws vibrator rod 461 against stop 462, thereby bending the normally straight vibrating spring 463 as shown in the drawing to give it sufficient potential energy to vibrate of its own elasticity on and off contact 430 for a sufficient number of cycles, when released by the magnet 450. The rod of vibrator 411 is likewise drawn over to stop 464 when the latter circuit is energized, and bends the spring 465 in the

same manner as the spring 463 was bent. The magnet 459 being energized pulls the armature 444 so as to move into engagement with the contact point 445. The armature of relay 438, after being moved against contact 70 440 by the energizing of its magnet 452, remains in that position when its coil is de-energized—held by the permanent magnetism of the relay—until it is moved back to contact 432 by outside means.

75 466 designates, in skeleton form, the principle and circuits of the receiving typewriter, comprising 436 units. Each unit is similar to unit 467 which comprises the soft iron cores 468 and 469 which are connected by soft iron yoke piece 470, these cores being wound with coils 471 and 472, respectively, in series and in a direction to induce opposite magnetic poles at the free ends of these cores; the soft iron core 473, fixed to the yoke piece midway between the other two cores, wound with coil 474 and supporting, or being near, at its free end the soft iron armature 475, which is pivoted at 476 just above the free pole of core 473 with its free ends equally distant from both outside pole pieces when the armature is in the open position; and the spring 477 for moving the armature upward. 478 is a connecting rod between the armature and the type bar 479; the latter being pivoted at the point 480. When current flows through the outside coils 471 and 472 only, the outside cores attract the armature 475 equally at both its ends, when it is in the open position, and cause no movement of the armature. When current flows through the center coil only, it likewise causes no movement of the armature, for the same reason. But, when both sets of coils are simultaneously energized the device operates in the well understood manner of a polarized relay, the center coil polarizing the armature, adding to the magnetism in the core 468 and detracting from the magnetism in core 469; and armature 475 will then be drawn down towards core 468, causing the type bar 479 to move up at its free end and imprint its character in the manner common to typewriters. The unit 480 represents the theory of the control of the functions of the typewriter, such as carriage return, line spacing, etc. It is similar to unit 467, except that it acts as a relay controlling through its armature 481 and front contact 482 the electromagnets 100 which perform said functions. The other 434 skeleton units represent units of similar construction, the desired number operating individual type bars and the remainder serving as relays, controlling the functions. The arrangement in the drawing of six horizontal rows and six vertical rows of six units each is merely for the purpose of illustrating the connections and circuits, which are 105 as follows: Conductor n^4 connects with the 110 115 120 125 130

upper horizontal row at the point 483 and current from battery lead m^4 passes through all the outside coils of the six units in this row, in series, and flows to common battery 5 return 484 at the point 485, when the mark selecting group of relays have selected this path; when conductor p^4 has been selected the path includes the outside coils of the six units in the second horizontal row from the 10 top, and connects with the battery return lead 484 at the point 486; when conductor r^4 has been selected the path includes the similar coils of the third horizontal row and connects with battery return 484 at the point 15 487; when the conductor s^4 has been selected the path includes the similar coils of the fourth horizontal row and connects with the battery return 484 at the point 488; when conductor t^4 has been selected the path 20 includes the similar coils of the fifth horizontal row and connects with the return 484 at the point 489, and when conductor u^4 has been selected the path includes the similar coils of the sixth horizontal row and connects with the return 484 at the point 490. In a similar manner the inside coils of the 25 six units comprising the first vertical row at the left as connected in series between the conductor 44 and the common battery return 491; the similar coils of the second vertical row between the conductor 45 and the same return, and the conductors 46, 47, 48 and 49 connect the similar coils of the third, fourth, fifth and sixth vertical rows, respectively, with the same return in the same manner—the conductors 44, 45, 46, 47, 48 and 49 being selected and connected with the battery lead 410 by the space group of selecting relays, as explained. When the 30 typewriter battery is applied it flows simultaneously through one of the vertical rows, according to the path that has been selected by the group of space selecting relays, and through one of the horizontal rows, according 35 to the path that has been selected by the group of mark selecting relays; and it is evident that one unit, and only one, will be energized thereby in both its outside and inside coils. That particular unit will operate; and other units, through which the current passes, will remain inoperative on account of being energized in only one set of coils.

492 designates a delayed action device 55 whose purpose is to discontinue the application of the typewriter battery after the proper interval of application. Its magnet 497 is energized simultaneously with the typewriter units 466, through the local circuit comprising typewriter battery 443, armature 444 and front contact 445 of relay 442, conductor 493, armature 439 and contact 440 of relay 438, conductors 494 and 495 and two joint paths, one of which 60 comprises battery lead m^4 and one of the mark

selecting relay paths through a horizontal row of typewriter units 466 to battery return 484 and the other of which comprises battery lead 410 and one of the space selecting relay paths through a vertical row of 70 typewriter units to battery return 491, and conductor 496. When energized, this magnet draws the armature 498 over against front stop 499. The inertia of the rod 4100 and weight 4101, supported by the vibrating 75 spring 4102 which is rigidly fixed to the armature as shown in the drawing, causes the rod to lag behind the armature in this movement for an interval, the length of which is regulated by the position of the 80 slidable weight 4101 upon the rod; and the rod then moves in the direction of the armature travel under the force of the bent spring 4102 which tends to return to its normal straightness. The apparatus is adjusted so that the tip 4103 of rod 4100 strikes the tip of armature 439 of relay 438 just after mark vibrator 428 has engaged its contact 430 on the first cycle after being released to vibrate. This allows the following 85 action to occur at the commencement of a mark pulse of a signal and while the delayed action device is completing this movement: Mark vibrator 428 makes one cycle that does not register on the mark selecting 90 relays on account of the lead being open at the contact 432 and strip 433 of relay 438—and the typewriter battery 443 is applied to the typewriter during this interval. When tip 4103 of rod 4100 strikes the 95 tip of armature 439 of relay 438, after this action has occurred, it moves armature 439 over against contact 432, thereby closing the circuit of mark vibrator battery lead 436 to vibrator contact 430, and opens the typewriter battery circuit at the contact 440 of relay 438; at the same time applying a 100 reset pulse from the typewriter battery 443 to the reset coils of all the selecting relays 105 of the two groups, through the local circuit comprising battery 443, armature 444 and contact 445 of relay 442, conductor 493, armature 439 of relay 438, tip 4103, rod 4101, spring 4102 and armature 498 of delayed action device 492, conductor 4104 (which includes in series the 110 reset coils of all the selecting relays) to the point 4105 on conductor 496, and conductor 496 to the opposite pole of the battery. The 115 application of this reset pulse lasts during the time tip 4103 of rod 4100 remains in contact with armature 439 of relay 438 in forcing it from contact 440 to contact 432. Magnet 497 of device 492 loses its magnetism 120 when the armature of relay 438 leaves contact point 440 and allows armature 498 to move to its back stop 4106 under the pull of its spring. The upper part of the device completes the movement of armature 439 to contact 432 by its own inertia and then 125 130

swings back and comes to rest against vibration absorber 4107. The latter comprises a weight, loosely pivoted at the point 4108. The foregoing operation of this device occurs while battery relay 442 is energized and is holding its armature 444 against front contact 445.

The operation of this apparatus may be briefly described as follows: Contacts 430 and 441 of vibrators 428 and 411 are adjusted so that they just clear the contact springs of their respective vibrator rods when vibrator springs 463 and 465 are in their normal position of straightness—as indicated by the position of vibrator spring 465 in the drawing. The slideable weights are adjusted upon the vibrator rods to make the rate of vibration the same as that of the vibrator at the transmitting station. Delayed action device 492 is adjusted as explained. Polarized relay 438 and all the polarized relays of the two groups of selecting relays are centered so that their armatures will rest against either stop when their respective coils are not energized, and pulse regulating relays 418 and 437 are adjusted so that the proper length pulse will pass to the selecting relays.

The position of the apparatus in the drawing, except that of the mark selecting relays, is the same as it should be just after line relay armature 446 has moved from front contact 455 (at the completion of the mark pulse of a signal) into engagement with back contact 448 (to register the space pulse of the same signal). Mark vibrator 428 has just been drawn over against stop 462; polar relay 438 has just moved its armature into engagement with contact point 440; relay 442 has just opened, and magnet 457 of space vibrator 411 has just released the vibrator rod from engagement with stop 464. To follow out the assumption that the mark pulse of the signal I am describing has just been registered, I will assume that mark selecting relays a^4 , b^4 , and c^4 have been set by this assumed mark pulse, and that their armatures are resting against the contacts g^4 , h^4 and i^4 , respectively; and that the signal being registered is the alphabetical signal comprising three mark and six space units, with one unit added to compensate for retardation.

The vibrator 411, released as described, will vibrate on and off contact 444 as long as line armature 446 remains against back contact 448. As the space pulse coming over the line from the sending station is 47 units in length, according to the relative adjustments of the transmitting and receiving vibrators, vibrator 411 will engage its contact 444 seven times and thereby put seven pulses of current through the battery leads 416 and 417; and space selecting relays v^4 , w^4 , x^4 , y^4 , z^4 , 42 and 43 will accordingly set

on the first, second, third, fourth, fifth, sixth and seventh pulses, respectively, thereby connecting the typewriter battery lead 410 with the sixth vertical row of typewriter units 466 from the left, through the tip 4109 of the armature of relay w^4 , contact 4110 of the same relay, conductor 4111, armature tip 4112 and contact 4113 of relay y^4 , conductor 4114, armature tip 4115 and contact 4116 of relay z^4 , conductor 4117, armature tip 4118 and contact 4119 of relay 42, conductor 4120, armature 4121 and contact 4122 of relay 43, and conductor 49.

Having registered the space pulse in this manner line armature 446 is moved against contact 455 under the control of the transmitting apparatus, to commence the mark pulse of the next signal and the following actions will occur, due to the opening of the local circuit controlled by this armature and contact 448 and the closing of the local circuit controlled by the armature and contact 455: Mark vibrator 428 will be released by its magnet and commence its vibrations on and off contact 430; the rod of space vibrator 411 will be drawn over into engagement with stop 464 and be made inoperative (being attracted by its magnet at the point in one of its swings where it is nearest to the magnet, as it was from this relative position that it commenced its vibrations) and relay 442 will close, thereby applying the typewriter battery 443 to the typewriter units 466 through the magnet coil of delayed action device 492. The armature of relay 438 will remain against contact 440.

The typewriter battery, applied by the closing of relay 442, flows through front contact 445 of that relay and over the described circuit through the armature and contact 440 of relay 438 and through the coil of magnet 457 of delayed action device 492 to typewriter battery lead 410, which is now connected with the conductor 49 at contact 4122 of space selecting relay 43, and thence through the center coils of the six units comprising the sixth vertical row of typewriter units from the left to battery return 491, and thence to the opposite pole of the battery through the conductor 496. Simultaneously, it flows through battery lead m^4 , from conductor 495, to the tip of the armature of mark selecting relay b^4 ; and thence through the particular horizontal row of typewriter units that were selected by the mark selecting relays in registering the mark pulse of the signal being described (which pulse was assumed to have set the mark selecting relays a^4 , b^4 , and c^4). The path of the current from the tip of the armature of relay b^4 back to the opposite pole of the battery would be, in that event, contact q^4 of relay b^4 , conductor 4123, tip 4124 and contact 4125 of relay c^4 , conductor 4126, armature tip 4127 and contact 4128 of relay d^4 , conductor r^4 , the

120
125
130

outside coils of the six typewriter units comprising the third horizontal row from the top to the point 487 on battery return 484, and conductor 496. Typewriter unit 4128 which is included in both the vertical and horizontal rows that are thus energized, will operate as described. Delayed action device 492 will operate in the manner explained during the application of the typewriter current, forcing armature 439 of polar relay 438 over against contact 432—thereby opening the typewriter battery circuit at the contact 440 and momentarily applying the reset current through the reset coils of the 15 selecting relays of both groups.

As before stated, the delayed action device is adjusted so that the vibrator 428 will have made one engagement with its contact 430 that does not register on the mark selecting 20 relays on account of armature 439 of relay 438 being out of engagement with contact 432. To compensate for this, the mark selecting relays are normally in position, when reset, to select the path through the typewriter units that represents one mark unit; and the mark group of selecting relays accordingly contains one less relay than the space group.

If no lengthening of the signals is desired, 30 mark selecting relay *a* and space selecting relay *v* can be made inoperative, as explained in connection with the similar relays of the transmitter. The above described signal will then register through the same 35 typewriter unit, as one less dot in both mark and space pulses will have been transmitted from the sending station for the signal. Greater lengthening of signals can be obtained by adding more extra dot relays to 40 the mark and space selecting groups, one to each group for each extra dot desired.

Describing next the apparatus shown in Figure 9:

*a*⁵ and *b*⁵ designate the sending and receiving 45 wheels, respectively, of a multiplex system, connected by the line wire *c*⁵ through the stationary brushes *d*⁵ and *e*⁵. They are assumed to be synchronized by some approved method not connected with my invention, so that when the wheels are revolving, the insulated metal sending segments *f*⁵, *g*⁵, *h*⁵, *i*⁵, *j*⁵ and *k*⁵ of wheel *a* maintain true 50 relative positions with the corresponding receiving segments *l*⁵, *m*⁵, *n*⁵, *o*⁵, *p*⁵ and *q*⁵, respectively, of wheel *b*⁵, thereby connecting each receiving segment to the line through 55 the brush *e*⁵ during the time its corresponding sending segment is passing under brush *d*⁵, in the usual manner.

*r*⁵ designates, in skeleton form, a transmitting set similar to the apparatus described in Figure 7 except that the vibrator and the pulse regulating relay (*a*³ and *s*³ of Fig. 7), are replaced by the stationary 60 brush *s*⁵ and the metal strip *t*⁵, the latter be-

ing carried on, and insulated from, the face of the wheel. Strip *t*⁵ makes contact with brush *s*⁵ as the former passes beneath the latter, thereby putting a pulse of current into the timing relay battery leads 70 *u*⁵ and *v*⁵ (*r*³ and *k*³ of Fig. 7), through the local circuit comprising battery *w*⁵ conductor *x*⁵, brush *s*⁵, strip *t*⁵, conductor *u*⁵, timing relays *y*⁵, *z*⁵, 52, 53, 54 and 55 and conductors 513 and 514, once 75 every revolution of the wheel *a*⁵. The duration of the pulses may be regulated by moving brush *s*⁵ toward or from the axle of wheel *a*⁵, as is apparent. The remaining apparatus of the sending set, being similar, is omitted 80 except that line transmitter 56 (polarized relay 399 of Fig. 7) is shown to illustrate the main line transmitting connections, which are as follows: When armature 57 of this relay engages contact 58 it applies battery 85 59 to sending segment *f*⁵ of wheel *a*⁵, through conductor 510, and when it engages contact 511 it applies the opposite and equal battery 512 to the same segment—the combination forming a polar transmission similar 90 to that employed in a polar duplex.

515 designates a similar transmitting set, connected to sending segment *k*⁵ by conductor 516 and receiving pulse currents for the 95 operation of its timing relays, etc., through strip 517, conductor 518, timing relays 519, 520, 521, 522, 523 and 524, conductors 525 and 514, battery *w*⁵, conductor *x*⁵ and brush *s*⁵—the brush *s*⁵ and pulse battery *w*⁵ being 100 common to both transmitting sets.

526 designates, in skeleton form, a receiving 105 set similar to the apparatus shown in Fig. 8, except that the vibrators 428 and 411 and the pulse regulating relays 437 and 418 of that drawing are replaced by stationary brush 527, metal strip 528 and polarized relay 529. The latter operates to close the pulse circuit through the mark selecting 110 relays 530, 531, 532, 533, 534 and 535 when armature 536 engages contact 537 and to close the pulse circuit through the space selecting relays 538, 539, 540, 541, 542 and 543 when armature 536 engages contact 544, through the local circuit comprising 115 common battery leads 545 and 546, common pulse battery 547, conductor 548, brush 527, strip 528, conductor 549, armature 536, and one or the other of the relay contact points and connected group of selecting 120 relays. The remainder of the set, being similar, is omitted, except line relay 550 which designates a polarized relay, the armature 551 and contacts 552 and 553 of which represent line armature 446 and associated contacts 448 and 455, of Fig. 8. This relay is 125 connected between receiving segment *l*⁵ and the ground by conductors 554 and 555, the coil of magnet 556 of relay 529 and conductor 557.

558 designates a similar receiving set, con-

nected to receiving segment q^5 and receiving its pulse current from common pulse battery 547, through strip 559, in the manner described for set 526—brush 527 and battery 547 being common to both sets.

The operation of this apparatus is as follows: When armature 7 of line transmitting relay 6 of sending set r rests against contact 11 it applies battery 12 to line c when segment f is passing beneath brush d and, as segment l of wheel b passes beneath brush e at the same instant, this battery flows from line c to segment l through brush e and thence to the ground through conductor 554, 10 the coils of relays 550 and 529 and conductor 557, causing relays 550 and 529 to move their armatures into engagement with contacts 553 and 537, respectively. When armature 57 rests against contact 58 it applies 15 opposite battery 59 to the channel in the same manner, which causes the armatures of receiving relays 550 and 529 to move in the opposite direction and engage contacts 52 and 44, respectively. When segment l is out 20 of engagement with brush e —during the greater part of each revolution of wheel b —the armatures of polarized relays 550 and 529 remain as positioned by the last contact 25 of this segment and brush, due to the holding force of the permanent magnetism of the relays.

The pulse currents that operate the transmitter are made effective when sending segment f is one half of a revolution 30 beyond line brush d , and its associated contact strip t is passing beneath brush s ; consequently, the movements of armature 7 of line transmitting relay 56 from one contact to the other, which occur only while a pulse 35 current is effective, will be made only when this segment is half a revolution beyond line brush d and no changes of applied current can occur in segment f while it is passing under line brush d .

40 At the receiving end, the pulse currents that operate the receiving apparatus are likewise effective one half of a revolution of wheel b after segment l passes line brush e . If the sending and receiving wheels are in 45 perfect synchronism the pulses will be effective at identical and precise intervals after any movement of the armatures of receiving relays 50 and 29—which can occur only at the instant segment l is passing beneath brush e .

The operation of sending set 15 and its associated receiving set 58 through sending and receiving segments h and q , respectively (and that of four other similar sending and receiving sets that may be used on the wheels shown in the drawing), will be similar to that of the sets and channel described.

Describing next the apparatus shown in Fig. 10.

55 α designates a selecting device through

which the perforated tape shown in Fig. 5 is automatically fed, comprising first, second and third element selecting needles b , c , and d , respectively, which are similar to the needles shown in Fig. 7 except that they 70 are positioned above tape e and engage the perforations therein, as f under the downward push of compression springs g , h and i ; contacts j , k and l , associated with the needles b , c and d , respectively; needle controlling lever m , positioned to engage projecting knobs n , o and p of the selecting needles from the under side; sprocket wheel q for moving the tape forward and lever r for controlling needle lever m through its 75 extensions s , and for turning sprocket wheel q through lever t which is pivoted on the free end of lever r and extends up behind the sprocket wheel where it engages the teeth of the wheel under the pull of spring u , in the usual manner. Magnet v and spring w control the movement of lever r between stops x and y , the coil of this magnet being included in the local circuit comprising conductor z , the coil of magnet 2 of 80 vibrator 3, conductor 4, battery 5, conductor 6, vibrator 3, contact 7 and conductor 8.

9 and 10 designate two polarized relays, controlled by the selecting needles and their associated contact points as follows: When needle b is moved downward through a perforation in the tape, as shown in the drawing, it closes the local circuit through coil 611 of relay 610 and coil 612 of relay 69, 95 comprising battery 613, conductor 38, contact j^6 , needle b^6 , conductor 614, coil 611, conductor 615, coil 612 and conductor 616; when needle c^6 engages a perforation it closes the local circuit comprising battery 617, conductor 618, needle c^6 , contact k^6 , conductor 619, coil 620 of relay 10, conductor 21, coil 22 of relay 9 and conductor 23 and when needle d^6 engages a perforation it closes the local circuit comprising battery 624, conductor 625, needle d^6 , contact l^6 , conductor 626, coil 627 of relay 610 and conductor 628. The coils of these two relays, when energized, cause the movements of their respective armatures in the directions indicated by the arrows on the coils; causing armature 629 of relay 610 to connect line wire 630 with the ground through contact 631 when third element needle d^6 enters a perforation; causing armature 629 of relay 610 to connect line wire 630 with the 100 armature of relay 69 and thence to negative battery 635, through contact 632 of relay 610, conductor 633 and contact 636 of relay 9, when second element needle c^6 enters a 105 perforation and causing armature 629 of relay 610 to connect line wire 630 with positive battery 634, through contact 632 of relay 610, conductor 33 and the armature and contact 637 of relay 69, when first element needle b^6 enters a perforation.

110

115

120

125

130

The operation of this apparatus is as follows: Vibrator 63, which operates in the same manner as the similar vibrator in Fig. 7, closes and opens the circuit energizing magnet v^6 of transmitter a once every cycle of vibration. When magnet v^6 is energized it draws lever r^6 down against stop x^6 , thereby raising needle controlling lever m^6 , which forces the selecting needles above the surface 10 of tape e^6 , and forcing sprocket wheel q^6 around one tooth's distance, through lever t^6 . When this magnet is deenergized spring w^6 pulls lever r^6 down against stop y^6 , thereby allowing needle controlling lever m^6 to 15 move downward by the pull of its retractile spring and permit the selecting needles to enter any perforations that may occur below them. It also pulls lever t^6 downward a sufficient distance to allow it to fall in behind 20 the next succeeding tooth of the sprocket wheel by the pull of spring u^6 , in the usual manner, so as to be in position to force the wheel around another tooth's distance when magnet v^6 is again energized.

25 Thus the tape is forced forward the distance of one feed hole every time the vibrator engages contact 67 and between contacts the needles are allowed to drop and engage the perforations in the tape. As only one of 30 the three element perforations occur opposite any one feed hole, polarized relays 610 and 69 are actuated as described and put a ground, negative battery or positive battery to the line accordingly as the perforations 35 representing these electrical conditions occur in the tape.

Describing next the apparatus shown in Figs. 11 and 11^a.

40 a^7 designates a main line polarized relay comprising permanent magnet b^7 ; soft iron pole pieces c^7 and d^7 , wound with coils e^7 and f^7 , respectively; soft iron armature g^7 ; spring h^7 and front and back contacts i^7 and j^7 , respectively.

45 b^7 designates a similar relay comprising permanent magnet l^7 ; soft iron pole pieces m^7 and n^7 , wound with coils o^7 and p^7 , respectively; soft iron armature q^7 ; spring r^7 and front and back contacts s^7 and t^7 , respectively.

50 These two relays are connected in series with main line u^7 , which extends from ground v^7 to point w^7 and thence to the distant station, the coils being connected in a direction to increase the permanent magnetism in the pole pieces of relay a^7 and decrease that in the pole pieces of relay b^7 when a positive current is flowing in the line from the distant station, and to decrease the permanent magnetism in the pole pieces of relay a^7 and increase that in the pole pieces of relay b^7 when negative current is flowing from the distant station. The retractile springs 55 are adjusted to overcome the permanent magnetism of the relays when no current flows

from the distant station, and to allow the armatures to be drawn against their respective front contacts when the magnetism of the pole pieces is increased as described. Hence, relay a^7 will close on positive current 70 from the distant station and open on negative or zero, and relay b^7 will close on negative and open on positive or zero.

x^7 , y^7 and z^7 designate three vibrators, 75 similar to those in Fig. 8, except that they are electro-magnetically controlled as follows:

Referring to vibrator x^7 . 72 designates a permanent magnet, having soft iron pole pieces 73 and 74. The latter are wound with coils 75 and 76, respectively, included in the local circuit comprising battery 77, conductor 78, front contact i^7 and armature g^7 , of line relay a^7 , conductors 79 and 710 and conductor 711. These coils are wound with the required number of turns and in a direction 80 to annul the permanent magnetism in the pole pieces when this local circuit is closed at line relay a^7 , which condition will release the vibrator from the position of strain shown in the drawing and allow it to vibrate 85 on and off its contact 712. When the above described local circuit is open at line relay a^7 the permanent magnetism in the pole pieces will attract soft iron vibrating rod 713 and draw it against stop 714, as shown 90 in the drawing.

Vibrator y^7 is similarly controlled through the local circuit comprising battery 715, conductor 716, armature g^7 and back contact t^7 of line relay b^7 , conductor 717, back contact j^7 and armature g^7 of line relay a^7 , conductors 79 and 718, coils 720 and 721 and conductors 722 and 723 and is released to vibrate on and off contact 724 when this local 100 circuit is closed by both line relays being in the open position, as shown in the drawing.

Vibrator z^7 is similarly controlled through the local circuit comprising battery 715, conductor 716, armature g^7 and front contact s^7 of line relay b^7 , conductor 725, coils 726 and 727 and conductors 728 and 723 and is likewise released to vibrate when line relay b^7 is in the closed position.

729, 730 and 731 designate three similar 115 tape marking devices, controlled by vibrators x^7 , y^7 and z^7 , respectively. They all may be described by referring to device 729, which comprises electromagnet 732, armature 733, spring 734, back stop 735 and marking point 736. The coil of magnet 732 120 is included in the local circuit comprising battery 738, conductor 739, vibrator x^7 , contact 712 and conductors 740, 741 and 742, and energize the device to draw marking point 736 against the surface of a moving 125 tape (an edge view of which is shown at 737) when vibrator x^7 engages its contact 712. Spring 734 moves armature 733 back against stop 735 when vibrator x^7 is not 130 engaging contact point 712.

Marking device 730 is similarly controlled by vibrator y^7 , through the local circuit comprising battery 738, conductors 739, 743 and 744, vibrator y^7 , contact 724, conductor 745, the coil of magnet 746 and conductors 747 and 742; and marking device 731 is similarly controlled by vibrator z^7 through the local circuit comprising battery 738, conductors 739, 743 and 748, vibrator z^7 , contact 749, conductor 750, the coil of magnet 751 and conductor 742.

Fig. 11^a designates a section of tape that is assumed to be moving at uniform speed in the direction of arrow 753, by mechanism not shown, and illustrates the fixed position of the armatures of the marking devices in relation to the moving tape—754 representing a back view of armature 733 of marking device 729, 755 representing a back view of the armature of marking device 730 and 756 representing a back view of the armature of marking device 731. The marking tips, which are on the under side of the armatures, directly opposite the points 757, 758 and 759, are normally just out of engagement with the tape and bear upon the surface of the tape when the devices are energized.

The operation is as follows:

The three vibrators are adjusted by their 30 slideable weights to the same period of vibration as that of the vibrator at the sending station. When the sending station puts the zero electrical state to the line, the line relays a^7 and k^7 will open as shown in the 35 drawing and release vibrator y^7 to vibrate, thereby causing marking device 730 to make a mark on the tape each time the vibrator engages its contact 724, as indicated by the three dots at 760. The other two vibrators 40 will remain inoperative during this zero state, on account of line relays a^7 and k^7 being open.

When the sending station puts positive battery to the line, line relay a^7 will close, 45 thereby causing vibrator y^7 to become inactive, through the opening of the local circuit of its magnet coils at contact j^7 of relay a^7 , and causing vibrator x^7 to be released to vibrate, through the closing of the local 50 circuit of its magnet coils at contact i^7 . Marking device 729 will accordingly operate with vibrator x^7 and mark the tape, as indicated at 761.

When the sending station puts negative 55 battery to the line, line relay a^7 will open and line relay k^7 will close. Vibrator z^7 will then operate, causing marking device 731 to register on the tape, as indicated at 762.

60 The signals on the tape are distinguished from each other by the zero element ending of each signal—each letter or character comprising the marks on the tape commencing with the positive or negative marks immediately following the preceding zero ele-

ment marks and extending to and including the next zero element marks to the right, as shown in the drawing. Thus, the signal between the imaginary lines 763 and 764 is composed of two positive units, followed by one negative unit, followed by three zero units. The next signal is confined between the imaginary lines 764 and 765 and consists of one positive unit followed by one zero unit.

76 The apparatus shown in Fig. 12 is as follows:

a^8 designates, as a whole, a combination sending and receiving apparatus at one station, of which:

80 b^8 designates a main line relay, of usual construction, whose armature c^8 operates between front and back contacts d^8 and e^8 , respectively.

f^8 and g^8 designate a pair of vibrators 85 similar to those shown in Fig. 8 and controlled in a similar manner by the armature and front and back contacts of relay b^8 , through two local circuits, one of which comprises battery h^8 , conductors m^8 and i^8 , the coil of magnet j^8 of vibrator f^8 , conductor k^8 , back contact e^8 and armature c^8 of relay b^8 and conductor l^8 and the other of which comprises battery h^8 , conductors m^8 and n^8 , the coil of magnet o^8 of vibrator g^8 , conductor p^8 , front contact d^8 and armature c^8 of relay b^8 and conductor l^8 .

90 q^8 , r^8 and s^8 designate three differentially wound polarized relays which are controlled by vibrator f^8 for the movement of their armatures to the right in the same manner as described in connection with the similar relays shown in Figs. 7 and 8; the magnet coils t^8 , u^8 and v^8 of these relays being connected across battery leads w^8 and x^8 , which latter are made active each time vibrator f^8 95 engages its contact, through the local circuit comprising conductor y^8 , battery z^8 , conductors 82 and 83, vibrator f^8 , contact 84, conductor 85, resistance 86, conductor 87 and said battery leads and magnet coils.

100 Relay q^8 , being normally connected across the leads w^8 and x^8 through the conductors 88 and 89, will move its armature to the right on the first pulse of current transmitted by vibrator f^8 and relays r^8 and s^8 will move their armatures likewise on the 2nd and 3rd pulses, respectively.

105 q^8 , r^8 and s^8 designate three differentially wound polarized relays which are controlled by vibrator f^8 for the movement of their armatures to the right in the same manner as described in connection with the similar relays shown in Figs. 7 and 8; the magnet coils t^8 , u^8 and v^8 of these relays being connected across battery leads w^8 and x^8 , which latter are made active each time vibrator f^8 110 engages its contact, through the local circuit comprising conductor y^8 , battery z^8 , conductors 82 and 83, vibrator f^8 , contact 84, conductor 85, resistance 86, conductor 87 and said battery leads and magnet coils.

115 Relay q^8 , being normally connected across the leads w^8 and x^8 through the conductors 88 and 89, will move its armature to the right on the first pulse of current transmitted by vibrator f^8 and relays r^8 and s^8 will move their armatures likewise on the 2nd and 3rd pulses, respectively.

120 810 designates a pulse regulating relay serving the same purpose as the same class relays shown in Figs. 7 and 8 and connected in a similar manner through the resistance 811 and conductors 812 and 813, for applying the shunt circuit comprising conductor 814, 125 armature 815 and front contact 816 of this relay and conductor 817 around the above mentioned coils of relays q^8 , r^8 and s^8 , each time vibrator f^8 engages contact 84. It differs from the similar relays shown in Figs. 7 and 8 in that it applies no shunt when its 130

armature rests against back stop 818; and the duration of the current pulse it permits to flow to the polarized relay coils is consequently equal to its lag plus the time consumed by its armature in moving from back stop 818 to front contact 816.

819 designates a sounder controlled by vibrator f^s through the local circuit comprising battery z^s , conductors 82 and 83, vibrator f^s , contact 84, conductors 85 and 820, and coil of magnet 821, conductor 822, contact 823 and armatures 824 of polarized relay s^s and conductors 825, x^s and y^s . It is energized to make an audible "dot" each time vibrator f^s engages contact 84, if its circuit is closed at contact 823 and armature 824 of polarized relay s^s .

826 designates a sounder similarly controlled by vibrator g^s through the local circuit comprising battery z^s , conductors 82 and 827, vibrator g^s , contact 828, conductors 829 and 830, the coil of magnet 831, conductor 832, contact 833 and armature 834 of polarized relay q^s and conductors 835, x^s and y^s .

Vibrator g^s also controls the movements of the armatures of polarized relays q^s , r^s and s^s , to the left, through the coils 836, 837 and 838, respectively; the latter coil being controlled directly by this vibrator to move armature 824 to the left on the first pulse of current and coils 837 and 836 being connected to move their associated armatures on the second and third pulses, respectively, in the step-up manner before explained.

839 designates a pulse regulating relay, similar to relay 810, connected between vibrator g^s and battery lead x^s for applying a shunt around coils 836, 837 and 838 of relays q^s , r^s and s^s respectively, in the same manner that relay 810 operates in connection with vibrator f^s and the other coils of these polarized relays.

840 designates a common telegraph key for opening and closing the line. This completes the apparatus at station a^s .

841 designates a similar arrangement of apparatus at the other station, comprising line relay 842, key 843 and a duplication of the local apparatus described for station a^s , which is indicated by the enclosure 844.

845 designates a main line connecting stations a^s and 841. Its circuit comprises ground 846, conductor 847, battery 848, conductor 849, key 840, conductor 850, the coil of relay b^s , conductor 845, the coil of relay 842, conductor 851, key 843, conductor 852, battery 853, conductor 854, ground 855 and the earth return.

80 The operation is as follows:

Vibrators f^s and g^s , at station a^s , and the corresponding vibrators at station 841 are adjusted by their slidable weights to the same period of oscillation. If it is desired to operate without lengthening the signals

to compensate for retardation, etc. contacts 833 of polarized relay q^s and 823 of polarized relay s^s are screwed against their respective armatures to keep the sounder circuits closed at these points. The set at station 841 is similarly adjusted.

Then, when key 840 is closed, vibrator f^s will be released and will vibrate on and off contact 84 and each contact will register on sounder 819 as an audible dot. When the key is opened vibrator g^s will operate and each engagement with contact 828 will register on sounder 826 as an audible dot. Consequently, to transmit, the operator merely holds the key closed for an interval during which sounder 819 makes the number of dots corresponding to the number of mark units in the signal, and then opens the key for an interval during which sounder 826 makes the number of dots corresponding to the number of space units in the signal—the sounders merely indicating to the operator the proper time intervals for holding the key closed and open.

Line relay 842, at station 841, will co-operate with relay b^s in the well understood manner and the corresponding vibrators at station 841 will accordingly be released to vibrate for corresponding intervals of time. The number of dots made on sounder 819 at station a^s will therefore be reproduced on the similar sounder at station 841 and the number of dots made on sounder 826 at station a will be reproduced on the corresponding sounder at station 841, thereby indicating to the operator at station 841 the number of mark and space units in the signal sent from station a^s .

It is desired to lengthen the mark and space elements of the signals to compensate for retardation, etc., the polarized relays at both stations are made operative by opening their contact points.

Referring to the apparatus at station a^s :

The contacts of polarized relays q^s , r^s and s^s are opened, as shown, and the armatures centered so that they will remain firmly held against either of their contacts when their respective coils are not energized.

The position of the apparatus in the drawing is as it should be immediately following the closing of the main line by either key—vibrator f^s having just been released by its magnet and is moving towards contact 84. Its first engagement with contact 84 will put a pulse of current through coil t^s of polarized relay q^s and cause that coil to move its armature into engagement with its right hand contact. The second contact of vibrator f^s with contact 84 will put a pulse of current through coil u^s of polarized relay r^s , and move the armature of that relay to the right. Up to this stage sounder 819 will not have operated, as its circuit is open at contact 823 of polarized relay s^s .

125 The second contact of vibrator f^s with contact 84 will put a pulse of current through coil u^s of polarized relay r^s , and move the armature of that relay to the right. Up to this stage sounder 819 will not have operated, as its circuit is open at contact 823 of polarized relay s^s .

The third pulse from vibrator f^s will move the armature of polarized relay s^s into engagement with its right hand contact, which will close the circuit of sounder 819 and allow it to operate on the remainder of the third pulse, and also on the following pulses as the armature of polarized relay s^s will remain in engagement with contact 823 until moved therefrom by the operation of vibrator g^s . The third pulse is, of course, shortened in its effect upon the sounder by the time consumed in moving the armature of polarized relay s^s into engagement with contact 823, but the action of the polarized relay is so fast that the sounder will operate satisfactorily on the remainder of the pulse at any degree of speed that can be read by ear.

When either key is opened the action of the apparatus a^s will be as follows:

Vibrator f^s will be made inoperative, as described, thereby terminating the dots that were being made on sounder 819, and vibrator g^s will be released to vibrate. The first current pulse transmitted by vibrator g^s and shortened by pulse regulating relay 839 will move armature 824 of polarized relay s^s to the left; the second pulse will move the armature of polarized relay r^s to the left and the third pulse will move the armature of polarized relay g^s into engagement with contact 823 and will also register on sounder 826. The succeeding pulses will register on sounder 826.

Thus, when the line is closed, by the closing of a key, the signal will register on one sounder as dots representing the number of units in the mark element of the signal, and when a key is opened the signal will register on another sounder as dots representing the number of space units in the signal—the same as if no additions had been made to the elements of the signal. The action of the polarized relays merely delays the audible recording of the mark and space elements an interval of two units each, during which time the sending operator holds the key open or closed as the case may be; and then maintains the position of the key while the signal is being audibly recorded on the sounders. Both sending and receiving operators read the signal by ear the same as if no additions had been made, the only difference being a slight pause between the operations of the mark and space sounders.

If an addition of only one unit is desired, polarized relay r^s of set a^s (and the corresponding relay of set 841) may be made inoperative by turning the contact points down against the armature, and if more than two units are required other polarized relays may be inserted between the polarized relays whose armatures directly control the

sounder circuits, and connected in a similar step-up manner.

The illustrations and description above given are merely intended to show practical modes of construction for my apparatus. References to positions of parts and directions of movements, such as upward and downward, right and left hand, vertical and horizontal, etc., refer to relative positions and movements when the parts are arranged as shown in the drawings. The particular details of construction above described are, however, variable to suit the ideas of the manufacturer, provided such variation retains the essential features of my invention.

I claim:

1. A telegraph alphabet consisting of signals, each signal consisting of a plurality of elements, each element being used but once in a signal each of said elements being varied in length relatively to each other and the relative lengths of the elements composing the signals being the point of distinction between signals composed of the same elements in the same sequence.

2. A telegraph alphabet consisting of signals, each signal consisting of a plurality of elements, each element in a signal consisting of one or more units of predetermined length, each element occurring but once in a signal and each signal being distinguished by the relative number of units in each element of which it is composed.

3. A telegraph alphabet consisting of signals, each signal consisting of a plurality of elements, each element in a signal consisting of one or more units of predetermined length, each element occurring but once in a signal and each signal being distinguished by the relative number of units in each element and the sequence of the elements of which it is composed.

4. A telegraph alphabet consisting of signals, each signal consisting of a plurality of elements, each element consisting of one or more units of predetermined length, the units of each element following each other in succession and without intermission and each signal being distinguished by the relation of the number of units of one element to the number of units of the other element or elements composing the signal.

5. A telegraph alphabet consisting of signals, each signal consisting of a plurality of elements, each element consisting of one or more units of predetermined length, the units of each element following each other in succession and without intermission and each signal being distinguished by the relation of the number of units of one element to the number of units of the other element or elements composing the signal and their order of occurrence.

6. In telegraphy, the method of communi-

cating by signals each composed of a plurality of elements, any element being used but once in a signal each of said elements being varied in length relatively to each other and the relative lengths of the elements composing the signals being the point of distinction between signals composed of the same elements in the same sequence.

7. In telegraphy, the method of communicating by signals each composed of a plurality of elements, each element being used but once in a signal and consisting of one or more units of predetermined length, and the signals being distinguished by the relative number of units in each element of which they are composed.

8. In telegraphy, the method of communicating by signals each composed of a plurality of elements, each element being used but once in a signal and consisting of one or more units of predetermined length, and each signal being distinguished by the number of units in each element and the sequence of the elements of which it is composed.

9. In telegraphy, the method of communicating by signals each composed of a plurality of elements, each element in a signal consisting of one or more units of predetermined length, the units of each element in a signal following each other in succession and without intermission and each signal being distinguished by the relation of the number of units in one element to the number of units of the other element or elements comprising the signal.

10. In telegraphy, the method of communicating by signals each composed of a plurality of elements, each element in a signal consisting of one or more units of predetermined length, the units of each element in a signal following each other in succession and without intermission and each signal being distinguished by the relation of the number of units in one element to the number of units of the other element or elements comprising the signal and the order of their occurrence in the signal.

11. In telegraphy, the method of overcoming line retardation, consisting in transmitting all the units of an element of a signal by a single electrical impulse equal in duration to the summation of the duration of the single units comprising it and causing only one electrical change in the line, prolonging the application of said electrical impulse to the line an interval sufficient to overcome retardation and discarding the resultant prolongations from the elements of the signals in the receiving apparatus.

12. In telegraphy, the method of reducing main line relay inertia losses, consisting in combining all the units of an element of a signal in the local circuits of the transmitting apparatus and transmitting them by one electrical impulse equal in duration to

the summation of the duration of the single units combined, prolonging the application of said electrical impulse to the line an interval sufficient to allow proper operation of the main line relays, and discarding the resultant prolongations from the element and disintegrating the element into its original number of units in the local circuits of the receiving apparatus.

13. In a telegraph means adapted to transmit the signals of an alphabet in which each signal is composed of a plurality of elements and each element is used but once in a signal, said means operating to make the duration of each element in a signal continue for one or more predetermined units of time and to arrange the elements in predetermined sequence without the necessity of a lapse of time.

14. In a telegraph means adapted to transmit the signals of an alphabet in which each signal is composed of a plurality of elements and each element is used but once in a signal, said means operating to make the duration of each element in a signal continue for one or more predetermined units of time and to arrange the elements in predetermined sequence, and each element in a signal being transmitted by different electrical impulses which do not require a lapse of time between them.

15. In a telegraph means adapted to transmit the signals of an alphabet in which each signal is composed of a plurality of elements and each element is used but once in a signal, said means operating to make the relative lengths of the elements composing each signal differ in signals composed of the same elements in the same sequence and to arrange the elements of the signals in predetermined sequence without the necessity of a lapse of time.

16. In a telegraph means adapted to transmit signals each composed of a plurality of elements of one or more units each, said means operating to group the units of each element in a signal and transmit them by one electrical impulse equal in duration to the summation of the durations of the single units grouped and to transmit the impulses in predetermined sequence without the necessity of a lapse of time between them.

17. In telegraphy, a pulse regulator of a source of periodic pulses of current, a divided circuit energized thereby one branch having a coil and the other an operative resistance, a contact connected to one terminal of said operative resistance by a conductor of relatively very low resistance, an armature connected to the other terminal of said operative resistance by a conductor of relatively very low resistance positioned to be moved by said coil against said contact when said coil is energized by one of said pulses of current and having means for mov-

ing it away from said contact between pulses of current, for applying a shunt around the operative resistance when said armature engages said contact, thereby permitting current to flow to the operative resistance only on the first part of each pulse of current while said coil is energizing and moving said armature against said contact.

18. In telegraphy, the method of communicating by signals which are composed of a plurality of elements, each element being used but once in a signal, and consisting of one or more units of predetermined length, the termination of each signal being

distinguished by the presence of a predetermined element, there being no break in the transmission of the elements.

19. In a telegraph alphabet consisting of signals, each signal consisting of a plurality of elements following each other without intermission, each element being used but once in a signal, and the relative lengths of the elements composing the signals being the point of distinction between signals composed of the same elements in the same sequence.

LAWRENCE CONNELL, JR.
